Primary Examiner — Karen E Eldridge Powers(74) *Attorney, Agent, or Firm* — Neal Gerber & Eisenberg LLP(57) **CLAIM**

The ornamental design for the ball cap for accommodating a bottle opener, as shown and described.

DESCRIPTION

FIG. 1 is an exploded front perspective view of the ball cap for accommodating a bottle opener of the present invention. The jagged broken line is merely illustrative to show how an exemplary bottle opener is accommodated by the ball cap for accommodating a bottle opener, and forms no part of the claimed design;

FIG. 2 is a top plan view thereof;

FIG. 3 is a side elevation view thereof; and,

FIG. 4 is an enlarged perspective view of the exemplary bottle opener shown in FIG. 1.

The broken lines in FIGS. 1-4 of the ball cap for accommodating a bottle opener are for the purpose of illustrating environment, and form no part of the claimed design.
